DESIGN FOR A BED JACKET OR SIMILAR ARTICLE

Morris Goldenstein, New York, N. Y.

Application April 8, 1941, Serial No. 100,218

Term of patent 3½ years

To all whom it may concern:

Be it known that I, Morris Goldenstein, a citizen of the United States of America, residing in New York city, county of Bronx, and State of New York, have invented a new, original, and ornamental Design for a Bed Jacket or Similar Article, of which the following is a specification, reference being had to the accompanying drawing, forming part thereof, wherein,

I claim:

The ornamental design for a bed jacket or similar article, substantially as shown.

MORRIS GOLDENSTEIN.
